UNITED STATES PATENT OFFICE.

HENRI BENIT, OF PARIS, FRANCE.

AUTOMATIC CIRCUIT-BREAKING SYSTEM.

Application filed January 13, 1927, Serial No. 160,979, and in Germany January 29, 1926.

In a generating station when a short circuit takes place on a feeder, this feeder may have to deal with the full short circuit current which the generators are able to supply 5 at that moment, if the short circuit occurs near to the station.

Therefore the circuit breaker placed on the feeder for the purpose of breaking this short circuit, must have a rupturing capacity corresponding to the full short circuit current 10 of the whole of the station.

A generating station with a large number of feeders must therefore be provided with a large number of high capacity circuit breakers 15 which only operate at rare intervals.

The purpose of the system which is the object of the present invention is to do away with these circuit breakers and to replace them by a single breaking system to which 20 the short circuited feeder is connected by means of a suitable switching arrangement at the moment it becomes necessary to break the circuit.

The invention is diagrammatically illustrated in the accompanying drawings.

In order to simplify the diagrams only one of the conductors of the circuits has been shown, the invention being applied in the same manner for single phase, two and three 30 phase current.

Figure 1 is a diagrammatic view of the assembled system, and

Figure 2 is a modified arrangement of the transferring switches.

References to these views will now be made by means of like characters corresponding to similar parts throughout.

1 are the usual main bus bars of the station; 40 2 are the alternators feeding these bars;

3, 3', 3'' are the various feeders;

4, 4', 4'' are switching devices which are in the position shown in 4 when the station is operating normally, establishing communication between the feeder 3 and the main bus bars 1. In moving towards the right these switches connect the feeder 3 with a second set of bars 5, which may be called interruption bars (without first breaking the connection with the bus bars 1) and then, by continuing their movement, break the connection between the main bus bars 1 and the feeder 3'' which, as shown in 4'', thus remains in communication only with the interruption bars.

These interruption bars 5 are themselves connected to the main bus 1 through a circuit breaker comprising a pair of heavy 50 contacts 6' and 6'' co-operating with a switching member 6''' to complete the circuit 6 which opens and breaks the circuit as soon as the switch 4 has reached its extreme position 60 towards the right.

As a large number of this circuit breaker 6 are not required it may without involving undue expense be of very solid design and have a very liberally calculated interrupting capacity.

The opening of the circuit breaker 6 is effected by the switch 4'' itself which at the end of its stroke makes contact at 7'' allowing current from a source of supply 9 to pass 70 through the releasing coil 8 of the circuit breaker 6.

The switching device 4 is operated in the usual manner by an overload relay 10.

It will be noted that the operation of the device 4 can only take place when the circuit breaker 6 is closed since the contacts 16 are then shorted and the coils 17 energized to keep the cores 18 in an extended position in the path of switches 4; and that this circuit breaker itself can not open unless the switch 4 has connected the feeder to the interruption bars.

As the switching devices 4 do not have to interrupt any current they may be of very 85 simple design either of the sliding contact type as shown diagrammatically on Fig 1, or they may consist of two separate circuit breakers as shown in Fig. 2.

These two circuit breakers 11 and 12 are 90 intended to connect the feeder 3 with the main bus bars 1 and with the interruption bars 5 respectively. Thus when the feeder is working normally the circuit breaker 11 alone is closed.

If a short circuit takes place the relay 10 first closes the circuit breaker 12 (position shown in the figure) and then the latter in closing causes the current from the source of supply 14 to flow through the contacts 13 100 to the releasing mechanism of the circuit breaker 11 which at the end of the stroke of the core 11' frees said mechanism and closes the contact 15; this allows current to flow through the coil 8 of the circuit breaker 105 6 and, consequently, causes the latter to open.

The bus bars 1 and 5, instead of being single as shown in the figure, should of course be double as is customary in all high tension plants, the various apparatus being 110 switched on to one or the other set of bars by means of two sets of disconnecting

switches. For safety and maintenance purposes two circuit breakers may also be provided in place of the single circuit breaker 6 shown in the figures, one or the other of 5 which is put into service by means of disconnecting switches, as above.

Finally the circuit breaker 6, in stead of being an ordinary breaking apparatus as shown diagrammatically in the figures, may 10 be designed in such a way that resistances or inductances are inserted progressively so as to gradually reduce the current before the circuit is broken.

Having thus fully described the invention, 15 what I claim as new and desire to protect by Letters Patent is:

1. A circuit breaking system for an electric generating station comprising a main bus bar or set of main bus bars and a plurality of feeders, characterized by the use of a single circuit breaker for disconnecting any defective feeder in case of short circuit, a switching device in each of said feeder circuits controlled by an overload relay in each 20 of said feeders therefor, said switching device automatically transferring the faulty 25

feeder from the main bus to an interruption bar connected to the main bus bars through said circuit breaker.

2. A circuit breaking system for the main 30 feeders of an electric generating station, characterized by the use of a single circuit breaker for disconnecting any defective feeder in case of short circuit, switching devices controlled by overload relays inductively coupled to a corresponding coil in series with each feeder, said switching device automatically transferring a faulty feeder 35 from the main bus bars of the station to an interruption bar connected to the main bus 40 bars through said circuit breaker, and means for controlling the operation of the circuit breaker so that the switching of a faulty feeder to the interruption bars cannot be done unless the circuit breaker is closed, and that the circuit breaker cannot open until the faulty feeder has been switched over to the 45 said interruption bars.

In witness whereof I have hereunto set my hand.

HENRI BENIT.
